TYPE-WRITING MACHINE.

1,119,922.

Specification of Letters Patent.

Patented Dec. 8, 1914.

Application filed June 2, 1914. Serial No. 842,358.

To all whom it may concern:

Be it known that we, CHARLES J. BOND and JOHN W. KOERNER, citizens of the United States, and residents of Syracuse, 5 in the county of Onondaga and State of New York, have invented certain new and useful Improvements in Type-Writing Machines, of which the following is a specification.

10 Our present invention relates to paper guiding and controlling devices or paper fingers, and its general object is to provide improved devices of the character specified.

More specifically stated, our improved paper 15 finger contrivances were constructed with a view to enabling them to be expeditiously and readily removed out of the path of the paper that is being fed over the platen, this being particularly advantageous 20 in connection with manifolding work since erasures may be readily effected on the separate sheets of the manifold pack.

The gist of our present invention resides 25 in connecting the paper finger proper or paper guide with the device on which it is supported or carried by a pivot or joint, the axis whereof is diagonal to the axis of the platen instead of parallel therewith as in prior constructions. This enables the paper 30 fingers to engage with the side margins of the paper and to be swung by a single pivotal movement away from the platen and laterally outside of or beyond the side edges of the paper so that the paper is quickly 35 freed for such manipulation as is desired.

To the above and other ends, our invention consists in the features of construction, combinations of devices and arrangements of parts hereinafter described and particularly pointed out in the claims.

In the accompanying drawings, Figure 1 is a fragmentary front elevation of the upper portion of a Monarch front-strike type-writing machine to which the preferred 45 form of the invention is shown as applied. Fig. 2 is a corresponding view showing the paper finger contrivances thrown off or in inoperative position. Fig. 3 is a vertical sectional view taken transversely of the platen on a plane indicated by the dotted line α — α in Fig. 1. Fig. 4 is a fragmentary plan view of the right-hand portion of Fig. 1. Fig. 5 is a fragmentary end view of the right-hand paper finger contrivance in its 50 inoperative or Fig. 2 position. Fig. 6 is a

perspective view of the carrier portion of one of the paper finger contrivances, together with the pressure spring for the paper finger proper. Fig. 7 is a fragmentary end view of a modified construction.

As appears from Figs. 1 and 3, the top plate 1 of the Monarch machine has rising from it brackets 2 to which are secured oppositely grooved guide rails 3, said rails cooperating through anti-friction balls 4 with the grooved rear-or-slide-bar 5 of the platen carrier or carriage, which further comprises forwardly extending end bars 6. Journaled on said end bars is the axle or spindle 7 of a rotary platen 8 with which is operatively connected a line spacing ratchet wheel 9, the same being adapted to be actuated and controlled by devices of ordinary construction not herein shown. The usual paper feeding or pressure rollers 10 and 11, Fig. 3, are provided for advancing the paper around the platen and upward at the front side thereof past a scale or scale plate 12 that extends lengthwise of the platen parallel with and below the printing line which is at the middle of the front face thereof.

The paper finger contrivances are mounted on a rod or bar 13 that is arranged above the platen and somewhat to the rear of the vertical plane passing through the platen axis, 55 said rod or bar 13 being detachably secured to the end bars 6. Preferably two paper finger contrivances embodying our invention are associated with the platen at its opposite end portions, these contrivances being 60 similar in construction but the paper fingers proper being off-set inwardly toward each other and the axes of their pivots being oppositely disposed. Each paper finger contrivance comprises a carrier or bracket that 65 is slidably supported on the rod 13 and a paper guide and pressure roll device that is connected with said carrier by a diagonal hinge or pivot, as hereinbefore stated. The right-hand carrier is shown detached in Fig. 100 6 and will be described in detail, it being understood that the description applies equally well to the left-hand carrier except that the axis or pivot supported thereon is oppositely disposed. This carrier, designated by the 105 reference numeral 14, is preferably made of sheet metal and is bent into a U-shape so that it comprises a web or connecting portion 15 and two forwardly extending ears 16 and 17. From the top of the ear 16 rises a 110

lug 18 while the forward portion of the ear 17 terminates in an upwardly extending lug 19. The ears 16 and 17 are formed with holes 20 to fit over the rod 13, and projecting inwardly from each hole is a lug or tongue 21 which cooperates with a groove 22 cut in the rod 13 and extending lengthwise thereof at its lower front side. This tongue and groove connection between the carrier 14 and its support or rod 13 enables said carrier to be slid along and adjusted at desired points lengthwise of the rod 13 while preventing said carrier from being turned or rotated on said rod. To hold the carrier in adjusted positions, friction means are provided comprising a spring 23, slightly bowed downward, which is confined between the ears 16 and 17 and is reduced at its ends to engage in notches 24 in said ears. As will be clearly understood from Figs. 3 and 4 the outer lug 19 of the right-hand carrier is forward of the inner lug 18, and both lugs are bent leftward at an angle to the planes of the ears 16 and 17, said planes being parallel and at right angles to the axis 7 of the platen as well as to the supporting rod 13. These lugs 18 and 19 are provided with holes in which is mounted a substantially horizontally disposed axle or pivot pin 25 for supporting the paper finger contrivance proper, and the axis of said pin is at an angle to the platen axis and to the rod 13 instead of being parallel therewith as in the ordinary construction. We have obtained satisfactory results by making the angle between the pivot pin 25 and the rod 13 substantially $32^{\circ} 30'$ but of course it is to be understood that such angle may be varied without departing from the invention.

The paper finger device proper comprises an arm 26 extending downward and forward over and in front of the platen, said rod at its rear being provided with downwardly extending ears 27 which are confined between the lugs 18 and 19 and are in planes parallel thereto. Said ears are perforated to fit over the pin 25 which serves as an axis about which the paper finger is adapted to turn. The rear end of said rod is also provided with a downward extension 28 that cooperates with an angular leaf spring 29 comprising a forwardly extending bowed portion or spring tongue that cooperates with the extension 28, said spring further comprising a downwardly extending portion that is arranged between the ears 16 and 17 of the carrier and is formed with a slot 30 that fits over a lug 31 turned forward and upward from the rear wall or web 15 of said carrier, the spring 29 being thus attachably supported on said carrier. From the pivot 25 the arm 26 extends horizontally forward for a short distance at right angles to said pivot and then 65 is bent downward and inclined rightward so that the major portion of said arm 26 is at right angles to the rod 13. Said arm terminates at its forward end in a curved finger portion 32. Near its end the arm is provided with an inwardly extending offset 33 to which is suitably secured a downwardly extending paper finger proper or guide 34, said guide curving downward and forward over the front face of the platen across the printing line and overlying the scale plate 12. The guide or guiding portion 34 of the paper finger is slotted, as indicated at 35, and the sides of the slot are upturned forming ears 36 which support the axis of a small rubber covered pressure roll 37 of ordinary construction, the pressure roll coöperating through said slot with the paper above the printing line. The pin or axle 25 of the hinged joint or pivotal connection between the guide proper and its support or bracket is also at an angle to a vertical plane passing longitudinally through the platen and is at an acute angle to a vertical plane passing transversely through the rod or bar 13 and the platen perpendicularly thereto, the line of the hinged joint being also at an acute angle to a vertical plane passing through the guiding portion of the paper finger and at right angles to the rod 13.

As stated, the left-hand paper finger contrivance is of substantially the same construction as is the right-hand contrivance heretofore described except that the pivot pin 25 is oppositely disposed and the off-set 33 projects inward to the right and toward the leftwardly projecting off-set 33 of the right-hand contrivance. The construction is such that the paper or work sheet, designated as *p* in Figs. 1 and 2, when it is fed up at the front of the platen past the scale plate 12, is guided by the guides or fingers 34 and pressure rolls 37 upward over the front of the platen, passing between the two arms 26 and the carriers 14, which are adjusted in conformity with the width of the sheet, and over the top of the rod 13. The paper fingers proper are held in coöperative spring pressed relationship with the platen and the paper thereon by reason of the pressure of the tongue portion of the spring 29 acting against the rear end portion 28 of the arm 26 back of the pivot 25. The end of this portion 28 is cut off substantially parallel with the pivot 25, and it is also inclined downward and rearward at an angle to the horizontal plane.

When for any purpose it is desired to free the paper that is advanced past the scale 12 it is only necessary to throw off the paper fingers or release them from operative relation with the platen, as illustrated in Fig. 2, this preferably being done by applying upward pressure to the finger portions 32. Because of our novel construction the paper fingers, as they are swung away from the 130

platen, instead of swinging upward in planes at right angles to the platen axis, swing directly in diagonal planes of rotation and are thus turned both upward and laterally outward away from each other, the pivotal axes being so disposed that this outward lateral movement of the paper fingers carries them outward beyond the side edges of the paper. It will be observed that the initial movement of the paper finger is about a diagonal axis and is outward away from the platen surface and also lateral. The carriers 14 being adjusted so that the side edges of the paper are normally inside of or between the arms 26, it will be understood that the throwing off of the paper fingers entirely frees that portion of the paper which is above or has been advanced past the scale plate 12. This is especially advantageous if corrections are to be made in manifold work as it enables the outer sheets of paper comprised in the manifold pack, together with the interleaved carbons, to be separately manipulated so that erasures may be made separately on said sheets. Such manipulation is well understood and it is not necessary to go into the details of it. Other advantages of our novel construction will occur to those skilled in the art.

It will be understood that as the pivotally mounted portions or guide fingers of the contrivances are swung upward and laterally outward as described, the end portions 28 will coöperate with the spring tongues, depressing said tongues, and that when the said fingers have been swung past the dead center said tongues will re-act against the portions 28 and will hold said fingers up in inoperative position as shown. Thus the springs 29 are double acting, serving both to apply operative pressure to the paper fingers normally and also to hold said fingers in inoperative positions.

Various changes may be made without departing from the principles of our present invention, and one illustration of such changes is shown in Fig. 7 wherein the bow spring 23 which frictionally holds the paper finger contrivance in adjusted position on the rod 13 is dispensed with and a single spring 38 is employed for providing friction between the paper finger carrier and its supporting rod, and also for applying pressure to the paper finger proper. Said spring engages frictionally with the top of the rod 13 and extends downward behind said rod between the walls of the carrier, pressing against the lower end of the web portion 15 of said carrier. Forward of the rod 13 said spring is curved upward and rearward, providing a tongue which coöperates with the extension 28. The construction is such that the spring re-acts against the rod 13 with sufficient friction to prevent lateral displacement of the paper finger contrivance on said rod while the upper end of said spring normally holds the paper finger proper down against the platen. Said spring also holds said finger off the platen when it has been swung to an inoperative position, and at this time the spring pressure against the rod 13 is lessened so that adjustments along the rod may be effected. We prefer, however, the first described construction employing the two springs as in practice it has been found difficult, from the manufacturing standpoint, to provide for the nicety of adjustment which the single spring construction requires.

Various other changes besides those herein specified may be made without departing from our invention; and it is of course to be understood that the invention may be applied to other styles of writing machines besides the Monarch typewriter herein illustrated.

What we claim as new and desire to secure by Letters Patent, is:—

1. In a typewriting machine, the combination with a platen, of a pivotally mounted paper finger, the pivotal axis about which the paper finger is swung initially outward away from operative relation with the surface of the platen being at an angle to the axis of the platen and so that the distance of the guiding portion of the finger from said axis increases.
2. In a typewriting machine, the combination with a platen, of a paper finger contrivance comprising a support and a paper finger pivotally connected with said support, said paper finger being swingable initially outward away from operative relation with the surface of the platen independently of said support, the pivotal axis about which said swing takes place being at an angle to the axis of the platen and so that the distance of the guiding portion of the finger from said axis increases.
3. In a typewriting machine, the combination with a platen, of a paper finger contrivance comprising a support and a paper finger pivotally connected with said support, said paper finger being swingable initially outward away from operative relation with the surface of the platen independently of said support, the pivotal axis about which the swing takes place being at an angle to the axis of the platen, and so that the distance of the guiding portion of the finger from said axis increases, the paper finger contrivance as a whole being movable in a direction parallel with the axis of the platen.
4. In a typewriting machine, the combination with a platen, of a paper finger contrivance comprising a support adjustable lengthwise of the platen and a paper finger proper pivoted on said support and having a pivotal movement independent of said sup-

- paper is directed by them over said rod or bar.
15. In a front-strike typewriting machine, the combination of a platen frame; a platen thereon; a rod or bar arranged above the platen and extending lengthwise thereof; and a pair of paper finger contrivances supported on said rod or bar and comprising portions extending downward therefrom over the platen surface across the printing line, said portions being swingable upward away from the surface of the platen, said portions during said upward swing at the same time moving laterally outward away from each other so that in abnormal position said portions are further separated than in normal position, the plane of revolution in which one of said portions swings or rotates intercepting the plane of rotation of the other portion, and spring means for holding said contrivances set in adjusted positions on said rod or bar, for maintaining said portions in spring pressed coöperation with the platen and also for holding said portions in inoperative positions after they have been swung away from the platen.
16. In a typewriting machine, the combination of a platen frame; a platen thereon; a rod or bar extending lengthwise of the platen; and a paper finger contrivance comprising a U-shaped carrier slidable on said rod and provided with ears carrying a pivot pin disposed at an angle to said rod or bar, and a paper guide pivoted on said pin, said guide being curved to conform to the platen surface and extending partly around the same.
17. In a typewriting machine, the combination of a platen frame; a platen thereon; a rod or bar extending lengthwise of the platen; and a paper finger contrivance comprising a U-shaped carrier slidable on said rod and provided with ears carrying a pivot pin disposed at an angle to said rod or bar, and a paper guide pivoted on said pin, said guide being curved to conform to the platen surface and extending partly around the same, said guide supporting a pressure roll which coöperates with the platen through an opening in said guide.
18. In a typewriting machine, the combination of a platen frame; a platen thereon; a rod or bar extending lengthwise of the platen; a paper finger contrivance comprising a U-shaped carrier slidable on said rod and provided with ears carrying a pivot pin disposed at an angle to said rod or bar, a paper guide pivoted on said pin, said guide being curved to conform to the platen surface and extending partly around the same, said guide being provided with an extension at the opposite side of said pivot pin, and a double-acting leaf spring carried by said carrier and coöperative with said ex-
- tension to hold said guide in spring pressed engagement with the platen, said spring also operating on said extension to hold said platen and said guide in released position when it is swung on said pivot away from the platen.
19. In a typewriting machine, the combination of a platen frame; a platen thereon; a rod or bar extending lengthwise of the platen; and a paper finger contrivance comprising a U-shaped carrier slidable on said rod and provided with ears carrying a pivot pin disposed at an angle to said rod or bar, said carrier having a tongue and groove connection with said rod, a spring for maintaining said carrier in adjusted positions along said rod, and a paper guide pivoted on said pin, said guide being curved to conform to the platen surface and extending partly around the same.
20. In a typewriting machine, the combination of a platen frame; a platen thereon; a rod or bar extending lengthwise of the platen; and a paper finger contrivance comprising a U-shaped carrier slidable on said rod and provided with ears carrying a pivot pin disposed at an angle to said rod or bar, said carrier having a tongue and groove connection with said rod, a spring for maintaining said carrier in adjusted positions along said rod, a paper guide pivoted on said pin, said guide being curved to conform to the platen surface and extending partly around the same, and an additional spring on said carrier and coöperative with said paper guide to maintain the same in spring pressed engagement with said platen, said additional spring operating on said guide to hold it in released position.
21. In a front-strike typewriting machine, the combination of a platen frame; a platen thereon; a paper finger rod above the platen and extending lengthwise thereof; a scale plate extending lengthwise of the platen below the printing line; and a pair of paper finger contrivances mounted on said rod, each contrivance comprising a carrier slidable along said rod and carrying a pivot pin above said rod and at an angle thereto; an arm pivoted on said pin and extending downward over the platen and toward the front side thereof, said arm being provided at one end with a finger piece and at its opposite end with an extension, a guide finger off-set inwardly from said arm and carried thereby, said guide finger extending over the front face of the platen and overlying said scale plate, and a spring on said carrier and coöperative with said extension.
22. In a typewriting machine, the combination of a platen, a platen frame, a paper finger rod on said frame, a paper finger contrivance comprising a carrier adjustable on said rod and a guide pivotally connected with said carrier; and a single spring effect-

tive to hold said carrier in adjustable positions along said rod to press said guide operatively against the platen and to hold said guide in released position when it is swung 5 away from the platen.

23. In a typewriting machine, the combination of a platen frame, a platen, a paper guide, and a support to which the guide is hinged, the axle of the hinge being arranged 10 in a substantially horizontal plane and at an angle to a vertical plane passing longitudinally through the platen, and said guide being initially movable out of operative engagement with the platen about said axle 15 as a pivot.

24. In a typewriting machine, the combination of a platen frame, a platen, a rod or bar extending lengthwise over the platen, a bracket mounted on said rod or bar, and a 20 paper finger hinged to said bracket, the axle of the hinge being arranged at an acute

angle to a vertical plane passing transversely through said rod or bar and said platen and perpendicularly thereto.

25. In a typewriting machine, the combination of a platen frame, a platen, a rod arranged parallel with the platen, a paper finger which when in operative position lies in a vertical plane at right angles to said rod, and means mounted on said rod and to 25 which said paper finger is hinged, the line of the hinge joint being at an acute angle to said vertical plane.

Signed at Syracuse, in the county of Onondaga, and State of New York, this 29 day 30 of May A. D. 1914.
